UNITED STATES PATENT OFFICE.

CHARLES S. BUTTERFIELD, OF MISSION, TEXAS.

EXCAVATOR.

1,219,371.

Specification of Letters Patent. Patented Mar. 13, 1917.

Application filed July 28, 1916. Serial No. 111,896.

To all whom it may concern:

Be it known that I, CHARLES S. BUTTERFIELD, a citizen of the United States, residing at Mission, in the county of Hidalgo and 5 State of Texas, have invented new and useful Improvements in Excavators, of which the following is a specification.

The invention relates to an excavator, and more particularly to the class of canal 10 excavating machines.

The primary object of the invention is the provision of a machine of this character wherein the buckets are automatically moved after the charging thereof for the discharge 15 of their load at opposite sides of said canal or upon the banks thereof, the hanging and mode of operation of the buckets being novel to assure the excavation of the work with despatch and the positive charging of 20 said buckets and the discharge of their contents.

Another object of the invention is the provision of a machine of this character wherein in a canal can be dredged, the working parts 25 of the excavator being supported upon pontoons which float from the body of water within the canal or channel and the booms and also the gunwale can be properly adjusted without excessive labor or inconvenience 30 to the user of the machine.

A further object of the invention is the provision of a machine of this character wherein the capacity thereof can be varied and said capacity will be under the control 35 of the strength of the boom, boom beams and power of the engine to pull drag lines.

A still further object of the invention is the provision of a machine of this character which is simple in construction, thoroughly 40 reliable and efficient in its operation, strong, durable and inexpensive in manufacture.

Other objects will be in part obvious and in part hereinafter set forth.

The invention accordingly consists in the 45 features of construction, combination of elements and arrangement of parts which will be exemplified in the construction hereinafter described, and the scope of the application of which will be indicated in the ap- 50 pended claims.

In the accompanying drawings:

Figure 1 is an elevation of an excavating

machine constructed in accordance with the invention;

Fig. 2 is a side elevation;

55

Fig. 3 is a fragmentary top plan view;

Fig. 4 is a view similar to Fig. 3, showing the dolly support and dollies therein, with the excavating mechanism removed;

Fig. 5 is a sectional view on the line 5—5 60 of Fig. 4, looking in the direction of the arrow;

Fig. 6 is a fragmentary vertical transverse sectional view through one of the dolly supports and dolly.

65

Similar reference characters indicate corresponding parts throughout the several views of the drawings.

Referring to the drawings in detail, A designates a pair of pontoons which are arranged side by side and are adapted to float and rise in a body of water within a canal, channel or the like, and between these pontoons is arranged a thrust or center board B which is of any ordinary well known 75 construction, it being understood, of course, that the length and width of each pontoon can be varied in accordance with the size of the canal or channel and also correspondingly to the capacity of the machine for the 80 proper and successful execution of the work in the dredging of a canal or channel. The pontoons A are connected together through the medium of end cross timbers C which are fastened thereto in any suitable manner. 85

Mounted upon the pontoons A at the top thereof are dolly supports 10 in which are arranged rollers 11 constituting the dollies, and upon these rollers are adapted to move the gunwale frame 12 which carries at one 90 end a boom beam 13 supporting a derrick hereinafter fully described.

Arranged at the desired point upon one or both of the pontoons A is a stationary engine 14 of any approved type which operates a pair of drums 15 and 16, the connection between the same and the said engine 14 being of any well known construction to permit the reversing of the drums 15 and 16 and the stopping and starting thereof when the occasion requires.

Adjustably connected to the boom beam 13 near the ends thereof are the booms 17 which extend in upwardly and forwardly

divergent relation to each other to opposite sides of the machine, while supported upon the gunwale frame 12 is the derrick including an inverted substantially V-shaped frame 18 having the braces 19, and to the head 20 of this frame 18 are connected the blocks and falls or tackle 21. The fall line 22 of each is adapted to be fastened to a clevis 23 carried by the frame 18, and connected with these blocks and falls 21 are the wire stake cables 24 which are also connected to the outer ends of the booms 17, as shown.

Mounted upon the outer ends of the booms 17 are drag line pulleys 25 over which are trained pull drag lines 26, preferably wire, the same being also trained over sheaves 27 located centrally on the boom beam 13 for the winding thereof on and from the drum 15, to which said lines 26 are connected, the same being also connected to drag buckets 28 preferably of the shape shown and are adapted to be charged from the bed of the canal or channel for the delivery of their contents to the bank or ground at opposite sides of the same in a manner presently described.

Upon the head 20 of the frame 18 are mounted drag line pulleys 29 over which are trained the back drag lines 30, preferably of wire, and connected to the buckets 28 and also to the drum 16 for the winding thereof on and the unwinding of the same therefrom when the machine is in operation.

Connected to the head 20 of the frame 18 which constitutes the derrick are wire cable guides 31 which are connected to a cross sill 32 at the rear end of the gunwale frame 13 and have therein turn buckles 33 for the tightening or slackening of each guide.

The gunwale frame 12 is moved backwardly and forwardly upon the roller 11 through the medium of a connection with a winch 34 supported upon one of the pontoons A and the same is operated in any suitable manner, although it may be operated from the engine 14 or otherwise.

It is to be understood, of course, that the pontoons A can be anchored within the canal or channel in any ordinary well known manner.

In the operation of the machine the buckets 28 are brought to the center of the pontoons by the back drag line 30 after the dumping of said buckets and then the same are lowered to be filled by the pull drag lines 26, whereupon said buckets are carried to the end of the booms 17 and finally tilted and dumped by the drag line 30, which will be clearly obvious, the lines 26 and 30 being wound upon and unwound from the drums 15 and 16 on the operation of the engine 14 which is controlled by an engineer. It will of course be understood that the back drag line 30 can be spliced to-

gether rearwardly of the derrick and in this event a single line from the point of the splice can be connected to for the winding thereof on and from the drum 16, and in this event either or both buckets 28 may be operated since the splice of the back drag lines 30 may be separated for the purpose of using either right or left back drag lines. Each bucket 28 carries a stirrup 35 to which each back drag line 30 is connected, and this stirrup has therein a pin 36 which, on the adjustment thereof, will regulate the tilt of the bucket to load fast or slow, as usual.

The buckets 28 are made from material sufficiently heavy to submerge themselves and also load themselves upon the proper movement of the drag lines 26 and 30, and are constructed to load and carry the number of cubic feet of excavated material desired, while the booms 17 can be readily adjusted and also the derrick, as the occasion may require.

From the foregoing description, taken in connection with the accompanying drawings, the construction and operation of the herein described excavator will be readily apparent, and, therefore, a more extended explanation has been omitted.

Having thus described my invention, I claim:

1. An excavating machine comprising a pair of pontoons, a thrust board arranged between the same, a gunwale frame movably supported upon the pontoons, a boom beam fixed to one end of the gunwale frame, a pair of booms adjustably connected to the beam, a derrick upon the gunwale frame, drums rotatably supported upon the pontoons, means connected with the derrick and the booms for suspending the latter, drag buckets, and pull and back drag lines connected with the buckets and with the drums for operation by the latter to move the buckets toward and away from each other and also for raising and lowering the same.

2. An excavating machine comprising a pair of pontoons, a thrust board arranged between the same, a gunwale frame movably supported upon the pontoons, a boom beam fixed to one end of the gunwale frame, a pair of booms adjustably connected to the beam, a derrick upon the gunwale frame, drums rotatably supported upon the pontoons, means connected with the derrick and the booms for suspending the latter, drag buckets, pull and back drag lines connected with the buckets and with the drums for operation by the latter to move the buckets toward and away from each other and also for raising and lowering the same, dolly supports on the pontoons, and dollies arranged in the supports and having the gunwale frame thereon.

3. An excavating machine comprising a pair of pontoons, a thrust board arranged

- between the same, a gunwale frame movably supported upon the pontoons, a boom beam fixed to one end of the gunwale frame, a pair of booms adjustably connected to the beam, a derrick upon the gunwale frame, drums rotatably supported upon the pontoons, means connected with the derrick and the booms for suspending the latter, drag buckets, pull and back drag lines connected 5 with the buckets and the drums for operation by the latter to move the buckets toward and away from each other and also for raising and lowering the same, dolly supports on the pontoons, dollies arranged in the supports and having the gunwale 35 frame thereon, guide pulleys on the boom beam, booms and derrick for the drag lines, and means for adjusting the gunwale frame.
5. An excavating machine comprising a pair of pontoons, a thrust board arranged 40 between the same, a gunwale frame movably supported upon the pontoons, a boom beam fixed to one end of the gunwale frame, a pair of booms adjustably connected to the beam, a derrick upon the gunwale frame, drums ro- 45 tatably supported upon the pontoons, means connected with the derrick and the booms for suspending the latter, drag buckets, pull and back drag lines connected with the buckets and with the drums for operation 50 by the latter to move the buckets toward and away from each other and also for raising and lowering the same, dolly supports on the pontoons, dollies arranged in the supports and having the gunwale frame there- 55 on, guide pulleys on the boom beam, booms and derrick for the drag lines, means for adjusting the gunwale frame, and means for operating the drums.
4. An excavating machine comprising a pair of pontoons, a thrust board arranged 20 between the same, a gunwale frame movably supported upon the pontoons, a boom beam fixed to one end of the gunwale frame, a pair of booms adjustably connected to the beam, a derrick upon the gunwale frame, drums ro- 25 tatably supported upon the pontoons, means connected with the derrick and the booms for suspending the latter, drag buckets, pull and back drag lines connected with the buckets and with the drums for operation 30 by the latter to move the buckets toward and away from each other and also for raising and lowering the same, dolly supports on the pontoons, dollies arranged in the supports and having the gunwale frame there- 35 on, guide pulleys on the boom beam, booms and derrick for the drag lines, means for adjusting the gunwale frame, and means for operating the drums.

In testimony whereof I affix my signature.

CHARLEY S. BUTTERFIELD.
